WILHELM FUNGS, OF LUDWIGSHAFEN-ON-THE-RHINE, GERMANY, ASSIGNOR TO I. G. FARBENINDUSTRIE AKTIENGESELLSCHAFT, OF FRANKFORT-ON-THE-MAIN, GERMANY, A CORPORATION OF GERMANY

BLEACHING ARTIFICIAL FATTY ACIDS

No Drawing. Application filed May 2, 1928, Serial No. 274,673, and in Germany May 20, 1927.

This invention relates to an improved process for bleaching artificial fatty acids.

I have found that the crude artificial fatty acids which means acids obtained by the oxidation with the aid of air or similar gaseous oxidizing agents containing oxygen of higher hydrocarbons of the paraffin series, or crude oxidation products containing the same, which often possess a dark color and unpleasant smell, are converted into high-grade, pale and sweet smelling products by treatment with a solution of substances which give off or transfer oxygen, the said substances being hereinafter referred to for the sake of brevity as agents supplying oxygen. Numerous oxidizing agents such as chromic acid, potassium permanganate, hydrogen peroxid and the like may be employed for this purpose. The employment of chromic acid in a medium previously acidified with another mineral acid or organic acid, other than those to be treated, has proved to be extremely satisfactory.

The method of working when employing chromic acid consists, for example, in stirring the crude artificial fatty acids or crude products containing the same, with dilute sulfuric acid or a solution of a chromic salt, so as to establish a fine state of distribution, heating the mixture, and then adding the amount of chromic acid solution requisite for bleaching, heating being continued. When the reaction is completed, the product is washed until free from chromium salts, and is then freed from water, for example by melting or by centrifuging.

The operation is preferably carried out at temperatures above 100° C. For example, the temperature is maintained at about 105° C. at the commencement of the bleaching and is raised to from 110° to 120° C. towards the end of the bleaching, and such rise in temperature may be established by concentrating the bleaching solution during the process, or by working under pressure. The temperature must not however be so high as to lead to a decomposition of the fatty acid.

The process according to the present invention may be modified in any suitable way according to the bleaching agent selected.

The said agent may be added in the cold or warm condition and the bleaching may be carried on in stages, by adding only a portion of the requisite amount of bleaching agent at first, drawing off the spent solution, then adding a further quantity of the fresh oxidizing agent, and continuing in the same manner until the desired bleaching effect has been produced. When chromic acid is used for the bleaching it is advisable, in case it is desired to regenerate the acid by electrolytic means, to begin with a concentration which will be suitable for such regeneration. The artificial fatty acids, or crude products containing the same, which are to be bleached may also be exposed to the action of the oxidizing agent after having been dissolved in a suitable solvent. Finally, the substances to be bleached may be subjected to a preliminary treatment with suitable solvents or absorbents and the like, or the bleached products may afterwards be treated with the said or similar agents, or both treatments may be beneficial.

By the treatment in accordance with the invention herein described, dark colored and malodorous artificial fatty acids, or crude products containing the same, are converted into light colored products of agreeable smell, which have an acid value of from about 200 to 270 and are of considerable value for the industries employing fatty acids and especially the soap industry.

The following examples will further illustrate the nature of the said invention which however is not limited thereto.

Example 1

250 grams of the dark malodorous products obtainable by the oxidation of paraffin, for example by rousing with air at an elevated temperature in the presence of solid bodies, which may be inert, or which may have a catalytic action, are treated with 3 liters of a 42 per cent sulfuric acid solution containing 100 grams of chromic acid, the mixture being stirred and heated to gentle ebullition. A concentrated aqueous solution (from 50 to 60 per cent strength) of 400 grams of chromic acid is then run in slowly, after which the reaction mixture is stirred

for 4 to 5 hours at from 105° to 110° C. and left at rest to cool down slowly. The oxidation product separates out as a solid, slightly greenish colored cake, on the surface of the aqueous solution. The traces of chromium compounds contained in the reaction product are extracted by boiling with 1 to 1.5 liters of a 10 per cent sulfuric acid solution, assisted by energetic stirring. The almost white product is boiled twice with distilled water in the same manner, in order to eliminate any residual traces of sulfuric acid. The resulting product is almost white and of agreeable smell reminiscent of coconut fat.

possible to above 100° C. and the current density is reduced somewhat towards the end of the bleaching process which requires from 4 to 10 hours depending on the degree of oxidation of the initial material.

70

Example 2

375 grams of the oxidation product from paraffin, obtainable by rousing paraffin with air at an elevated temperature in the presence of solid bodies, which may be inert, or which may have a catalytic action, are emulsified by stirring into 4.5 liters of gently boiling 42 per cent sulfuric acid. A highly concentrated aqueous solution of 540 grams of potassium permanganate is run into the boiling reaction mixture in the course of two hours, and the mixture is kept stirred at a temperature above 100° C. for from 2 to 3 hours. When the reaction is completed, the paraffin oxidation product is treated with dilute sulfuric acid as in Example 1. Any traces of manganese dioxide present in the resulting product may be removed by melting the product while adding an adsorbent, such as bleaching earth, filtering the hot mixture after carefully stirring it, the manganese dioxide being adsorbed by the bleaching earth and retained on the filter. The resulting product has the same character as that obtained according to Example 1.

When the said oxidation products of paraffin have been sufficiently bleached, the current is switched off, and the stirrer brought to rest whereupon the bleached products separate out from the liquid. The bleached product which is pale green in color is drawn off while still hot and worked up as described in Example 1. The product which has thus been purified has a similar consistency to that described in Example 1.

75

What I claim is:

1. A process for bleaching crude substances obtained by the destructive oxidation of high molecular paraffins and containing artificial fatty acids, and obtained by oxidizing higher hydrocarbons of the paraffin series with gases containing oxygen which comprises treating the said crude substances with a solution of agents supplying oxygen while warming to at least 100° C. but not so high as to lead to a decomposition of the fatty acids.

85

2. A process for bleaching crude substances obtained by the destructive oxidation of high molecular paraffins and containing artificial fatty acids and obtained by oxidizing higher hydrocarbons of the paraffin series with gases containing oxygen, which comprises treating these with a solution of agents supplying oxygen at temperatures above 100° C. but not so high as to lead to a decomposition of the fatty acids.

90

3. A process for bleaching a crude malodorous brown oxidation product of paraffin containing artificial fatty acids and obtained by treating paraffin with gases containing oxygen which comprises treating the said product with a solution of chromic acid in aqueous sulfuric acid at a temperature of from 105 to 110° C.

105

In testimony whereof I have hereunto set my hand.

WILHELM PUNGS.

115

Example 3

A lead reaction vessel is charged with sulfuric acid of 40 per cent strength containing 50 grams of chromic sulfate per liter. The said lead vessel serves as an anode and is connected with the positive pole of a source of electric current. The cathode may consist of any metal which is stable against the action of the electrolyte for example of lead, and preferably has the form of a stirrer. After the solution contained in the said reaction vessel has been heated to about 90° C. so much of an oxidation product of paraffin obtainable by rousing the said paraffin with air at an elevated temperature in the presence of solid bodies which may be inert or have catalytic action, is added thereto with energetic stirring that about 80 grams of the said oxidation product are introduced for each liter of the solution and the electric circuit is then connected. The voltage employed is about 3 to 5 volts and the current density amounts to about 500 amperes per square meter. The temperature is slowly raised if
